UNITED STATES PATENT OFFICE.

CROMWELL A. B. HALVORSON, JR., AND JOHN T. BEECHLYN, OF SAUGUS, MASSACHUSETTS, ASSIGNORS TO GENERAL ELECTRIC COMPANY, A CORPORATION OF NEW YORK.

LIGHT ATTACHMENT.

1,287,298.

Specification of Letters Patent. Patented Dec. 10, 1918.

Application filed July 3, 1917. Serial No. 178,485.

To all whom it may concern:

Be it known that we, CROMWELL A. B. HALVORSON, Jr., and JOHN T. BEECHLYN, citizens of the United States, residing at 5 Saugus, county of Essex, State of Massachusetts, have invented certain new and useful Improvements in Light Attachments, of which the following is a specification.

Our invention relates to a lamp guard and 10 the method of making the same, and has for its object the improvement in the manufacture of a device of this character. The guard made in accordance with our invention may also be of such form that it may at the same 15 time reflect the light from the protected lamp in the desired direction.

Our invention will best be understood by reference to the accompanying drawings, in which we have shown one embodiment of 20 our invention, and in which: Figure 1 is a plan view of a sheet metal blank stamped to form, when properly expanded, a lamp guard embodying one form of our invention; Fig. 2 is a perspective view showing 25 the parts of Fig. 1 expanded; Fig. 3 is a side view partly in section showing the guard of Fig. 2 surrounding an incandescent lamp bulb and secured in place by attachment to the lamp fixture, and Fig. 4 is a view similar to Fig. 3 showing a slightly different form of our invention, in which parts of the guard serve also as reflectors.

Referring to the drawing, the blank shown in Fig. 1, is a circular sheet metal disk A, 35 from which certain parts are removed so as to form the central ring 10 and the spider arms 11 extending from the ring 10 outwardly. In addition to this a number of spaced narrow slots or incisions are made in 40 the outer part of the disk in such form and extent as to mark off the rings 12-13 and 14, concentric with the central ring 10. Of these incisions those marked 15, 16, 17 and 18 are concentric circular arcs, and the incisions 45 19-20 are radial, connecting one end of each of the incisions 15 and 16 with the next adjacent ends of the incisions 17 and 18. In the drawing 12 sets of circular arc incisions are indicated, but a greater or smaller number 50 may be used.

The segmental strips included between each pair of concentric incisions 15, 17, constitute tongues 21, which connect the outermost ring 12 with the next inner ring 13,

and the segmental strips included between 55 each pair of concentric incisions 16, 18, constitute like tongues 22, which connect the ring 13 with the ring 14, while the spider arms 11 connect the ring 14 with the central ring 10. When the metal has been stamped 60 in the form shown in Fig. 1, then to form the lamp guard, it is only necessary to expand the metal, either by hand or by a die, by holding the outer ring 12 stationary and forcing the other sections away from it to 65 bring it into the form shown in Fig. 2.

In Fig. 3 the lamp guard is shown surrounding an incandescent lamp bulb 23 which is to be protected and is attached to a lamp fixture 24. In this form the rings 10, 12, 13 and 14 are substantially horizontal so 70 as to intercept but a negligible amount of light. The connecting strips 21, 22 and 11 are also parallel to the rays of light so that the latter are not substantially obstructed 75 thereby. The device embodying our invention illustrated in Figs. 1, 2 and 3 is primarily intended as a lamp guard though it will of course be understood that the flat rings may, if desired, be arranged to reflect 80 the light. When this is desired however we prefer to make the device of the form shown in Fig. 4 in which we have shown a lamp guard formed in the same manner as that shown in Figs. 1, 2 and 3 with the exception 85 that the flat rings are made wider than those of Figs. 1, 2 and 3 and are so positioned with reference to the emitted light as to reflect all or a part of it in a desired direction. In the structure shown in this figure, the reflecting 90 rings 25 and 26 located above the light source are preferably arranged horizontally, so that upwardly directed rays of light 30 and 31 will be reflected by the rings 25 and 26 downwardly in a useful direction, as 95 shown. The reflecting rings 28 and 29 below the light source are preferably arranged at an angle to the horizontal so that downwardly directed rays of light 32 and 33 which impinge upon the reflecting rings 28 and 29 will be reflected below the horizontal but at a smaller angle thereto than the direct rays 32 and 33, the former being a more useful direction for most purposes as is well understood. In this construction, the ring 100 27 which is in substantially the same horizontal plane as the light source, is narrower than the remaining reflecting rings, and is

not intended to re-direct the light but is arranged parallel to the rays so as not to obstruct the same.

While we have here shown the reflecting rings or vanes arranged to reflect the light at a small angle below the horizontal, it will of course be understood that they may be arranged to reflect the light in any desired direction.

10 While we have described our invention as embodying a concrete structure and as operating in a specific manner in accordance with the provisions of the patent statutes, it should be understood that we do not limit 15 our invention thereto, since various modifications thereof will suggest themselves to those skilled in the art without departing from the spirit of our invention, the scope of which is set forth in the annexed claims.

20 What we claim as new and desire to secure by Letters Patent of the United States, is,—

1. A lamp guard comprising a plurality of vertically spaced flat and substantially horizontally disposed rings, and tongues or 25 strips integral with and spacing the rings.

2. A combined lamp guard and reflector comprising a plurality of vertically spaced, substantially flat rings forming an inclosure for the light source and adapted to reflect 30 the light therefrom, the rings being con-

nected together by strips integral with the reflecting rings.

3. In combination, a light source, and a combined lamp guard and reflector surrounding the same and comprising a plurality of substantially flat substantially horizontally disposed reflecting rings connected together by integral strips. 35

4. In combination, a lamp bulb, and a combined guard and reflector therefor comprising a plurality of substantially flat reflecting rings surrounding the bulb, the reflecting surfaces of which are positioned to reflect the intercepted light downwardly in the desired direction, the rings being connected together by integral strips. 40

5. In combination, a light source, and a combined lamp guard and reflector surrounding the same and comprising a plurality of substantially flat reflecting rings connected together by integral strips, the reflecting rings above the light source being substantially horizontal and those below the light source at an angle to the horizontal. 50

In witness whereof, we have hereunto set 55 our hands this 30th day of June, 1917.

CROMWELL A. B. HALVORSON, JR.
JOHN T. BEECHLYN.
